UNITED STATES PATENT OFFICE.

JOHN F. RUTT, OF CHICAGO, ILLINOIS.

WATCHMAN'S CLOCK.

Application filed February 5, 1923, Serial No. 616,916. Renewed June 6, 1928.

My invention relates to watchmen's clocks of the class which are carried from one station to another by a watchman and which are operated by him at each station by means of a 5 fixed station key to make an impression on a movable dial and thereby form an automatic record of his movements. It is one of the objects of my invention to provide a simple, light and comparatively inexpensive device 10 for the object indicated. Further objects of my invention are to provide means by which the locking operation of the closing lid will make a time record of its action on the dial whenever it is opened or closed; so to 15 construct the dial and its attachments that the dial may be accurately secured to a moving arbor in proper registration with the clock movement; to provide a novel device for embossing distinctive station marks upon 20 the dial; to provide a novel combination of the key-way and keys of such relative construction as to preclude falsification of the record made by the embossing apparatus; to make the keys of cheap and simple construction 25 and further to provide a special system of characters by which the number of keys and the capacity of separate registrations may be extended to any desired limit without enlarging the clock or increasing the number 30 or size of its constituents parts.

The principles of my invention are illustrated in the drawings in which Fig. 1 shows a front view of the recording dial of my improved clock; Fig. 2 is a vertical section of the 35 clock on the line 2—2 of Fig. 1; Fig. 3 is a section on the line 3—3 of Fig. 1 looked at from below; Fig. 4 is an enlarged section on the line 4—4 of Fig. 1 showing the cover securing apparatus in locked position; Fig. 5 is a similar 40 view showing the same parts in relatively different positions; Fig. 6 is an enlarged sectional view of the upper portion of Fig. 2 showing different relative positions of certain 45 parts; Fig. 7 is a section on the line 7—7 of Fig. 6; Fig. 8 is a perspective view of a dial embossing "key" and the under side of a matrix plate adapted to co-operate therewith; Fig. 9 shows a series of characters adapted to use on the "key"; and Fig. 10 50 shows a fragmental recording dial.

Further describing my invention with reference to the drawings in which like characters of reference denote like parts throughout; numeral 1 represents the body of a suitable enclosing box and 2 a cover attached thereto by hinge 3. Within the body of the

said box is the framework 4 of a suitable clock movement having an observation dial 5 with the usual hands 6 and 7 attached to minute and hour arbors in the usual manner. At 60 the rear of the clock framing is a circular dial plate 9 forming an enclosing wall for the clock movement. Upon the inner face of said plate is mounted the hour arbor which passes through plate 9 and carries a disk 10 65 which should be partially seated in a depression in the face of plate 9 and extended slightly thereabove. The outer portion of the said arbor is enlarged and provided with a left hand screw 12 adapted to take the binding 70 nut 13 which should be of the exact circumference of the disk 10, upon which it is seated and between which and the under face of the binding nut the paper recording dial 15 is clamped. 75

The recording dial 15 consists of a disk of heavy paper in the ordinary form, having radial lines corresponding to the movements of the hour arbor and should be rigidly secured thereto by means of the clamping device. As a means of determining and fixing the exact relation of the two dials to each other, I provide an offset pin 17 attached to and projecting outwardly from the periphery of disk 10. There should be a corresponding 80 aperture 18 in the paper dial and the pin should be set so closely to the periphery of the binding member or nut 13 that the dial cannot be caught between them but must be placed in proper registration before the binding nut can be seated in place. 85

A bridge piece 20 is carried across the one edge or segment of the dial plate 9, being spaced therefrom by the curved or spacing piece 21. Its normal position is determined 90 by pins 22 and it is removably secured in place by screws 23. A rock shaft 25 is journaled on the bridge piece and has a knife 26, or other marking instrument, radially attached to the inner end thereof. A spring 27 100 provides means by which the knife is normally held out of the cutting and marking position. The said rock shaft is further provided with a hook 28 adapted to engage with a corresponding hook or latch 29 attached 105 to the inside of the cover 30. The outer end of the rock shaft is squared as shown at 25' or otherwise adapted to take an operating key 31. It will be seen that the interlocking hooks or latches perform the further function, when 110 the case is either being opened or closed, of causing the knife 26 to make a notch or de-

pression in the paper dial and thus register the times at which the case was locked or opened. A depression 35 in the plate 9 permits the knife, as shown in Fig. 5, to cut entirely through the paper dial. The same rotating movement locks or unlocks the case and causes the knife to make a cut in the dial and thus indicates the time of such opening. It will be seen that the inner mechanism of the case can not be tampered with, without leaving the evidence of the case having been opened. The associated device by which the successive station records are made comprise in the full plan a matrix plate 38 on the under side of the bridge piece just above and adjacent to the face of the paper dial. The face of said matrix plate is provided with predetermined characters which correspond to characters on a "key" 40 which is introduced through the slot 41 in the casing. A key-way adjacent to said slot is formed by the lateral walls 43 and the enclosing partition 44. The "key" shown in perspective in Fig. 8 may comprise a shaft 45 and a head 46. The head is provided with a plurality of lateral longitudinal depressions 47 into which lead transverse depressions or notches 48. A further depression 49 is formed at the operating end of the head. Dies 50 are formed on the upper edge of the body portion corresponding to depressions in the matrix plate 38. There is a further depression 51 on the upper edge of the key-shaft 45, adjacent to the head. It corresponds to a pin 51' in the plate 9, while the depression 49 corresponds to a fulcrum pin 49' in the partition 44. Guide pins 52 project inwardly from the lateral walls of the key-chamber, and, into the key-chamber also project a plurality of anti-friction balls 53 which are held in normally advanced position by means of springs 54 and tap-screws 55. When it is desired to make a record, the particular key at the station to which it is attached is thrust by a straight line motion into the slot 41, its movement in the key-way being guided by the pins 52 operating in the lateral slots 47 until the fulcrum pin 49' is received within the opening 49. A slight upward movement of the key-shaft causes the gripping balls to leave the lateral slots and pass across the portion of the key-head indicated by the dotted line in Fig. 6, until they pass the dead centers formed at the lower edge of the key causing the balls to bite thereon. The "key" is thus turned upward on the fulcrum pin 49' causing a sudden blow or impact of the character 50 upon the underside of the paper dial at a point corresponding to the similar depression in the matrix plate. An embossed figure or character is thus formed on the face of the paper dial which shows the corresponding period of clock movement and forms a record of the time and of the station at which it was made, as is hereinafter explained. As

the "key" swings upward on the fulcrum pin 49' the guiding pin 52 enters the lateral slot 48 thereby holding the "key" in operative position while the pin 51' enters the depression 50 in the key-shaft thus further establishing accurate registration.

The paper dial shown has twelve divisions, set off by heavy radial lines, corresponding to the hours from one to twelve. Each main section is divided by three light radial lines into four sections representing fifteen minutes each. There are also a number of lines representing concentric circles on the dial forming ten annular spaces. An individual character or figure representing each station is placed on the upper edge of the "key" appropriated thereto so that the character representing that station will be spaced from the pivot pin by a distance corresponding with one of the depressions in said matrix. The embossing apparatus will then mark the dial so that the time will be indicated by the position with reference to the radial lines and the place by reference to the annular spaces. It will be understood that, by proper mechanical arrangement, dials may be used having spaces for twenty four or other number of hours if desired.

In the common practice of using consecutive numerals the capacity of a machine is limited to those numerals because each numeral must have its corresponding matrix depression. If additional stations are required to be added it can only be done by enlarging the machine involving large additional cost.

But I have discovered that by using a standard symmetrical character for all the matrix depressions and a corresponding character and fragmentary portions thereof on the edge of the key-head an almost limitless number of stations may be provided for, with only the addition of a simple and inexpensive key for each and without any additional weight in the clock itself. In Fig. 8 I have shown the face of the matrix having ten depressions in the form of an X. As each one represents one of the annular spaces on the dial, embossing faces 50 such as shown spaced in regular order on the edge of the key will show definitely the movements of the watchman. Should additional capacity be desired beyond the ten keys already provided for, another set of keys to the number required may be used having sub-characters. These may be formed, for example, from the left hand part of the X-figure as shown at "b" in Fig. 8. Another series of ten keys may have marking characters like "c" in the drawings. Each one will be printed distinctly by that portion of the complete X in the matrix to which it corresponds. By the series of characters indicated, as high as one hundred keys may be used and the capacity of the machine be extended accordingly without increase of size,

weight or cost except for the keys and they may be added one at a time if desired. It will further be noted that other fundamental matrix figures as, for instance, a circle can 5 be used. In this case, embossing faces forming a whole or any portion of the circle can be used, while, by using a combination of the X figure and the circle for the matrix and sub-portions of either or both for the 10 embossing faces, the number of indications may be almost without limit. I have explained this phase of my invention by reference to a matrix having all the depressions in the form of the fundamental character and 15 the use thereof in the first set of keys; the second set of keys all having the first set of sub-characters and so on. But it is also practical to use one matrix depression with any desired sequence of sub-characters on 20 the keys. That is, instead of exhausting the positions in order with each character, the characters and sub-characters may be exhausted in their order with reference to each 25 position.

25 I claim:

1. In a watchman's clock; a rotatable dial, a matrix substantially in contact with one face thereof, a key-way adjacent to the other

face thereof, and a key or lever having a character on one edge corresponding to a 30 character on the matrix, said key being fulcrumed at the inner end of said key-way by a ball and socket connection to swing on its fulcrum and co-operate with the matrix and emboss said character on the dial. 35

2. In a watchman's clock; a rotatable dial, a matrix substantially in contact with one face thereof, a key-way adjacent to the other face thereof, and a key or lever having a character on one edge corresponding to a 40 character on the matrix, said key being fulcrumed at the inner end of said key-way to co-operate with the matrix and emboss said character on the dial, guiding means to fulcrum the key and means to cause the character in the key when so fulcrumed to register with the corresponding character in the matrix, the key fulcrum including a socket in the end of the key and a pin at the inner end of the key-way to be received in the key 45 socket. 50

In witness whereof I have hereunto set my hand at Chicago, Cook County, Illinois, this 31st day of January, 1923.

JOHN F. RUTT.
